CLAIM

The ornamental appearance for a vertical kiosk terminal, as shown and described.

DESCRIPTION

FIG. 1 is an isometric view of a vertical kiosk terminal in accordance with an illustrative embodiment;

FIG. 2 is a front facing view thereof;

FIG. 3 is a back view thereof;

FIG. 4 is a left side view thereof;

FIG. 5 is a right side view thereof;

FIG. 6 is a top view thereof; and,

FIG. 7 is bottom view thereof.

Broken lines included in the figures, including any boundary created thereby, illustrate environmental matter only and do not form a part of the claimed design.
